DECORATIVE FABRIC FOR HANDBAGS

Rose Jackler, Brooklyn, and Daisy H. Goldberg,
New York, N. Y.

Application September 27, 1944, Serial No. 555,964

4 Claims. (Cl. 41—10)

1

This invention relates to handbags of the type which comprise a bag body, the exterior of which is decorated with pieces or strips of wood, plastic, or other suitable material.

Bags of this general type have heretofore utilized decorative elements in the form of strips or squares, secured on the exterior of the bag body by means of cords or tapes threaded through the several elements and attached to the bag body by sewing, staples or the like. This method of attachment is unsecure and unsatisfactory. The threading of the elements into the cords or tapes and the attachment of these cords or tapes to the bag body is tedious and time consuming, and great care must be exercised to get all of the cords or tapes under the same correct tension. If too tight, they are apt to break after a short interval of use and if too loose, they permit separation of the elements so that the fabric of the bag body may be seen between them. As the elements are usually washable and the bag body not conveniently so, the fabric soon becomes soiled or unsightly and the bag is generally discarded long before its usefulness has ceased. Moreover, there is considerable friction on the cords or tapes where they pass through the decorative elements and this causes undue wear and frequent breakage which is difficult and costly to repair.

The primary object of this invention is to eliminate the disadvantages to which we have referred, and others, and to so improve upon bags of this general type that their decoration may be highly efficient, strong, durable and sightly at all times.

Speaking generally, the decorative elements of this invention are arranged in edge to edge relation and formed to interfit with one another. These interfitting parts constitute the knuckles of a hinge connection between them, and are perforated for the passage of rods or wires which constitute the hinge pins or pintles. The elements are so arranged that each hinge pin wire serves a plurality of joints and in practice it is entirely feasible to extend the hinge pin wires for the full length and for the full height of the bag. In fact, such wire may be passed back and forth through the interfitting knuckles of several or all of the horizontal and vertical rows of elements, if desired. However, we prefer to use a separate wire to secure each two adjacent rows of elements together, because this arrangement facilitates repair if, through accident, one or more of the elements are broken.

Other objects and features of this invention

2

will be apparent from the following detailed description and appended claims, when read in conjunction with the accompanying drawings in which:

- 5 Figure 1 is a perspective view of a hand bag embodying one form of the present invention.
 Figure 2 is a fragmental perspective showing more clearly the joint between two adjacent strips of the kind illustrated in Figure 1.
 10 Figure 3 is a perspective view showing decorative elements of different shape than those shown in Figure 1. The several elements here illustrated, are shown as separated from one another, i. e., unjoined, so that their structure may
 15 more clearly appear.

Figures 4 and 5 are fragmental perspective views showing different ways of forming the hinge knuckles on the decorative elements.

Referring first to Figures 1 and 2 of the drawing, the reference characters 1—1 designate two border strips which may, if desired, form part of a bag frame. They may be provided at their upper edges with catch members (not shown) of any conventional kind, such as slide fasteners, 20 throw-over locks, snap fasteners, draw-strings, or like means for normally holding the bag in closed condition. These border strips are secured to the bag body 2, which may conveniently comprise a lining or other appropriate backing, 25 provided at its opposite ends with gussets, and attached to the border strips by staples, stitches, adhesive or the like, indicated generally at 3.

The reference character 4 designates a plurality of like decorative elements, in the form of 30 elongated strips. These strips may be of an appropriate thickness and material. They are consecutively arranged in edge to edge relation to one another and to the border strips 1 and their contiguous edges, as well as the lower edges 35 of the border strips, are cut away or castellated to form the knuckles of 5 and 7 of hinge joints between each two adjacent strips. The knuckles of each strip are spaced apart longitudinally thereof by intervening cut-outs 8 and 9, which 40 receive said knuckles in substantially aligned horizontal, overlapping relation in the direction of the length of the bag. The knuckles are provided with aligned longitudinal perforations, and hinge pins, in the form of wires or rods 10, are 45 passed through said aligned perforations to hold the strips in interfitting relation while permitting articulation between them. To allow of free articulation without binding and at the same time to insure joints which will conceal the 50 underlying portion of the lining 3, the edges of 55

the cut-outs 8 and 9 and the substantially abutting edges of corresponding knuckles 6 and 7 are complementarily curved on the axis of the pivot wires, as clearly shown in Figures 1 and 2.

The opposite termini of the several wires 10 are preferably bent over or headed so that they will not inadvertently slide out. If so desired, the strips 4 may also be secured to the lining by stitches, or otherwise, although such attachment is not essential.

In the construction of Figures 1 and 2, the decorative element strips 4 are shown as extending the full length of the bag but, if desired, these strips may be subdivided longitudinally into shorter lengths to provide smaller elements 4a such as illustrated in Figure 3. In this showing, each of the smaller decorative elements 4a is provided, at two adjacent edges, with single knuckles 11 and 12, respectively and at its other two adjacent edges with twin knuckles 13 and 14, respectively. The knuckle 11 of each element is adapted to project between the knuckles 14 of the juxtaposed element directly above it, while the knuckle 12 is adapted to project between the knuckles 13 of the next horizontally adjacent element.

It should be noted in this connection, that the knuckles 11 are positioned adjacent the forward face of each element 4a, and that the knuckles 12 are positioned adjacent the rear faces. Consequently, when the elements are assembled in interfitting relation, the horizontal hinge pin wires 10a, which pass through aligned perforations in the knuckles 11 and 14, will be in front of and hence will not interfere with the upright hinge pin wires 10b which pass through like perforations in the knuckles 12 and 13.

It will be understood that, when the structure of Figure 3 is employed, it is preferably associated, at the upper edges of the bag, with border strips similar to the strips 4 of Figure 1, but provided horizontally with knuckles and intermediate cut-outs of proper shape and spacing to cooperate with the hinge joint parts of the two uppermost rows of elements 4a.

It is practical, with such a construction as shown in Figure 3 to extend the horizontal rows of the elements entirely around the bag so as to conceal the gussets which are shown as exposed in Figure 1. It is likewise practical to interpose two or more of the short elements 4a between the adjacent ends of each pair of corresponding horizontal strips 4 at the opposite sides of the bag shown in Figure 1, by providing the opposite ends of these strips 4 with knuckles like 12 and 13 of Figure 3 and offsetting the horizontal and upright hinge wires after the manner explained in connection with the latter figure.

The hinge pin wires employed are sturdy enough to maintain the knuckles, through which they pass, in substantially aligned relation but still allow of such flexing of the wires as will insure reasonable flexibility of the decorative assembly as a whole when in place on the bag body to form a covering therefor.

We have referred to the knuckles of the hinge joints as being perforated. The perforations may be formed by merely providing hinge wire holes as by boring, casting, or other similar operation, or they may be formed as shown in Figure 4 in such a way that the slot 16 extends from each perforation 15 to the outer end of the corresponding knuckle. The purpose of this slot 16 is to permit the parts to be extruded through the use of appropriate extrusion dies, for the slot

16 will permit of the supporting of the die core which forms the perforation 15 during the extrusion operation. Slot 16 should be of appreciably less width than the diameter of the perforation

15 and of the hinge wire 10, so that the hinge wire cannot pass through the slot 16. This arrangement has been shown in Figure 4 as adapted to the construction of Figures 1 and 2, although it may be employed in the construction of Figure 10 3.

Figure 5 shows another way of forming the perforations 15 of the hinge knuckles. Here the decorative elements are initially provided with extending flanges 17a, as shown in dotted lines in this figure, and these flanges are thereafter bent or curled, as shown at 17 in the full lines, to form the hinge knuckles with the perforations 15 therein. Figure 5 shows the adaptation of this modification to the type of element illustrated in Figure 1, but it may of course be employed in connection with the smaller elements of Figure 3.

In practically carrying out this invention, the respective decorative elements may be of various 25 color or materials to produce a wide variety of designs. They may be easily assembled by unskilled labor and, in the event of breakage, can be readily repaired, or any particular element or elements may be removed and replaced by 30 simply withdrawing appropriate hinge pin wires. The parts are practically indestructible when subjected to ordinary wear and the elements fit so closely together that the lining will not show through. When once assembled they cannot 35 separate as is so commonly the case with the cord and tape constructions. Moreover, the wear on the hinge pin wires is negligible.

The foregoing detailed description sets forth the invention in certain preferred practical 40 forms, but the invention is to be understood as fully commensurate with the appended claims.

Having thus described the invention, what we claim as new and desire to secure by Letters Patent is:

45 1. A decorative covering for a bag, the covering comprising decorative elements arranged in superimposed horizontal rows extending from end to end of the bag, with the lateral edges of the elements of each row castellated to consecutively interfit with one another, and the upper and the lower edges of the elements of adjacent rows also castellated to interfit with one another, and flexible hinge pin wires extending horizontally and vertically through perforations in said 55 interfitting castellations to secure said elements to one another for relative pivotal movement.

2. A decorative covering for a bag, the covering comprising decorative elements arranged in superimposed horizontal rows extending from

60 end to end of the bag, with the lateral edges of the elements of each row castellated to consecutively interfit with one another, and the upper and lower edges of the elements of adjacent rows also castellated to interfit with one another, and

65 flexible hinge pin wires extending horizontally and vertically through perforations in said interfitting castellations to secure said elements to one another for relative pivotal movement, said horizontal and vertical hinge pin wires being respectively positioned at different distances from the outer faces of said decorative elements so as to clear one another at their points of crossing.

70 3. A decorative covering for a bag, the covering comprising decorative elements arranged in superimposed horizontal rows extending entirely

around the bag body, with the lateral edges of the elements of each row castellated to consecutively interfit with one another, flexible hinge pin wires extending through perforations in said interfitting castellations to hingedly secure the elements of such rows together, the upper and lower edges of the elements of adjacent rows being also castellated to interfit with one another, and flexible hinge pin wires extending through perforations in said last mentioned perforations to hingedly secure the elements of adjacent rows together.

4. A decorative fabric for a handbag comprising: decorative elements, each of which is provided along each of its longitudinal edges with spaced apart flanges curled upon themselves to form aligned hinge knuckles between which that edge of the element is concave for close fitting articulation with the hinge knuckles of the next adjacent element, and hinge pins extending through the hinge knuckles of each two adjacent elements to secure them to one another for relative pivotal movement.
